UNITED STATES PATENT OFFICE.

CARL A. JOHNSON, OF WORCESTER, MASSACHUSETTS, ASSIGNEE OF ONE-HALF TO
ARTHUR R. PETERSON, OF WORCESTER, MASSACHUSETTS.

TAKE-UP BLOCK.

Application filed August 11, 1924. Serial No. 731,532.

To all whom it may concern:

Be it known that I, CARL A. JOHNSON, a subject of the King of Sweden, residing at Worcester, in the county of Worcester and 5 State of Massachusetts, have invented a new and useful Take-Up Block, of which the following is a specification.

This invention relates to a take up block for wire galvanizing, tinning and annealing 10 machines. In this class of machines the wire does not ride up the drum normally as it does on a wire drawing machine drum and consequently the operators have to go around the plant and push up the wire from 15 time to time. This involves unnecessary expense for attendance of the machines but the principal disadvantage is that it is done irregularly and consequently when a bundle 20 of wire is wound on the block it is all snarled up and is not in good condition for the next process.

The principal object of this invention is to provide automatic and regularly acting 25 means for moving the wire up the surface 25 of the block a little at a time at regular intervals so as to leave the wire in a smooth untangled condition on the block and avoid the waste of time heretofore thought necessary.

Reference is to be had to the accompanying drawings, in which—

Fig. 1 is a plan of a take up block constructed in accordance with this invention shown partly in section; and

Fig. 2 is a central sectional view of the same on the line 2—2 of Fig. 1.

I have not shown the machine to which the device is applied, but it can be used on galvanizing, tinning or annealing machines 40 for handling wire and the invention relates to the drum 10 on which the wire is wound. In fact the drum with this improvement is capable of general use. This drum is shown as usual fixed by its hub 12 on a shaft 11 rotated in any desired way. This drum is of the usual character having a conical surface on which the wire coils as the machine operates.

For the purpose of the present invention, 50 I fix on the hub 12 of the drum a cover plate 13 having three arms 14 radiating therefrom and integral with this cover plate as shown. Each of these arms is provided with a perforation for receiving a tangential shaft or stud 15. Swingly mounted

on each stud is a lever 16 having a roll 17 at the bottom engaging the exterior surface of a cam 18 which is mounted in fixed position below the drum and causes the levers 16 to be rocked on their axes once during 60 each rotation of the drum in opposition to their springs 19. Each lever has a pawl 20 resting on a ratchet wheel 21 mounted to freely rotate on the shaft 15. Therefore at each complete revolution of the drum the 65 ratchet wheel is advanced one tooth.

On the ratchet wheel is fixed a wire engaging and lifting plate 22. If there are twenty teeth on the ratchet wheel 21, the plate 22 thereon will come around once in 70 twenty revolutions. That is, when twenty convolutions of wire are wound on the drum, and project out through a slot 23 in the side of the drum. As it rises it engages the lower strands of the wire on the drum and 75 lifts them, starting at the dotted line position shown at the right in Fig. 2. These twenty convolutions are lifted by the three teeth 22 spaced equally around the drum and not all operating simultaneously but all 80 operating at the same revolution. In this way the wire is slid up the surface of the drum gently and yet positively and it will not tangle up on the surface but the twenty convolutions ordinarily will rise together. 85 There is a gravity actuated stop pawl 24 for preventing the wheel 21 moving backwardly.

Fixedly mounted on each arm 14 is a support 25 having a pointed end projecting 90 through the slot 23. The lower side of the projecting end of the arm 25 is slanted so that the wire will pass over it when forced up positively by the tooth 22, the upper edge of which at that time is horizontal or tipped 95 up slightly so that the wire will not be disengaged from it on account of that angle. The wire is pushed up this incline and over the support 25 which thereafter holds the wire up in that position and prevents its 100 falling back by gravity after once being pushed beyond it. It is to be noted that the pushing of the wire over this projecting end of the support 25 requires a little give in the wire. Usually it is wound slack 105 enough so that this will take place without any trouble but it is to be observed that the three supports 25 are not subjected to this action at the same instant so that all the slack can be available for each one. 110

In this way the wire is automatically pushed up the drum as many times as may be necessary, kept from getting tangled up, and held in a position above that at which the new wire is being wound. The saving in labor is also an important feature.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described but—What I do claim is:—

1. The combination with a take up block for a wire galvanizing, tinning or annealing machine, of means located inside the block and projecting through the walls thereof for moving a plurality of coils of wire along the surface of the block every time the block makes a predetermined number of revolutions.

2. In a take up block for a wire working machine, the combination with the block itself, of a plurality of means projecting through the wall of the block for moving a coil of wire along the surface of the block, and means for operating said means one at a time during a single rotation of the drum.

3. The combination with a take up block for a wire galvanizing, tinning or annealing machine, said block having slots through its walls, of movable means projecting through said slots for periodically raising the coils on the outside of the block and relatively stationary means for holding them in elevated position.

4. The combination with a rotary wire drawing block, of means for consecutively engaging the lower part of a coil of wire thereon at a plurality of points around the circumference and raising the coil at those points one at a time.

5. The combination with a take up block 45 for a wire galvanizing, tinning or annealing machine, and a shaft for rotating it, of a stationary cam located outside the drum, a plurality of arms inside the drum, a series of levers pivoted on said arms and 50 adapted to be operated once during each revolution of the drum by said cam, a pawl on each lever, a ratchet wheel pivoted on the axis of each lever in a position to be actuated in a step by step manner by the pawl, said ratchet wheel having a lifting plate projecting through the wall of the drum for raising the coil of wire along the surface of the drum once during a predetermined 55 number of revolutions of the drum. 60

6. The combination with a take up block for a wire galvanizing, tinning or annealing machine, and a shaft at the center thereof for rotating it, of a stationary cam located outside the drum, a plurality of arms 65 inside the drum extending from the hub thereof, a series of levers pivoted on said arms and adapted to be operated once during each revolution of the drum by said cam, a pawl on each lever, a ratchet wheel pivoted on the axis of each lever in a position 70 to be actuated in a step by step manner by the pawl, said ratchet wheel having a plate projecting through the wall of the drum for raising the coil of wire along 75 the surface of the drum once during a pre-determined number of revolutions of the drum, and a fixed arm extending through the wall of the drum in a position to receive and hold the coils of wire pushed upwardly 80 by said plate on the ratchet wheel, said ratchet wheels being arranged to operate one after the other during one revolution of the drum.

In testimony whereof I have hereunto 85 affixed my signature.

CARL A. JOHNSON.
